UNITED STATES PATENT OFFICE.

WILLIAM MIDDLEITCH SCOTT, OF BIRMINGHAM, COUNTY OF WARWICK,
AND CHARLES PROCTOR, OF HANDSWORTH, COUNTY OF STAFFORD,
ENGLAND; SAID PROCTOR ASSIGNOR TO SAID SCOTT.

BREAKDOWN GUN.

SPECIFICATION forming part of Letters Patent No. 288,670, dated November 20, 1883.

Application filed September 6, 1883. (No model.) Patented in England August 8, 1883, No. 3,859.

To all whom it may concern:

Be it known that we, WILLIAM MIDDLE-
DITCH SCOTT, of the firm of W. and C. SCOTT
& SON, of Birmingham, in the county of
5 Warwick, England, gun-manufacturers, and
CHARLES PROCTOR, of Handsworth, in the
county of Stafford, England, gun-maker, sub-
jects of the Queen of Great Britain, have in-
10 vented certain new and useful Improvements
in Breech-Loading Small-Arms, (for which ap-
plication for provisional protection in England,
dated August 8, 1883, No. 3,859, has been
made,) of which the following is a specifica-
15 tion.

Our invention has reference to breech-load-
ing small-arms of the kind commonly known
as "dropdown guns;" and it consists in the
following arrangement and combination of
20 parts for effecting the cocking of the ham-
mers of the said dropdown guns on the rais-
ing of the breech ends of the barrels from the
break-off for the purpose of charging them.

In the body of the gun is an opening pass-
ing obliquely from below the axis on which
25 the barrels and fore-end turn to the rear end
of the body and terminating opposite the
breast of the hammer. In this hole a rod
somewhat longer than the hole slides, the said
rod being urged toward the muzzle end of the
30 gun by a coiled spring. At the joint part of
the fore-end, and near its upper face, is a pin,
on which a cranked lever turns. The short up-
per arm of this lever is nearly horizontal and
the long arm nearly vertical. The short arm
35 of the said lever bears upon a shoulder made
on the front end of the body, and the long
arm of the said lever bears against the lower
end of the sliding rod described. When the
muzzle end of the barrel is depressed for the
40 purpose of raising the breech end, the center
on which the cranked lever turns is depressed
with it. This depression of the center on which
the cranked lever turns causes the said lever
to turn upon its center, the short arm of the
45 lever being prevented from descending by the
shoulder on the body on which it bears. By
the action described the long arm of the cranked
lever moves toward the break-off, pushing for-
ward the oblique sliding rod, the upper end

of which, bearing against the breast of the ham- 50
mer, raises and cocks the hammer. The cocked
hammer is retained in position by the ordi-
nary sear, and bent when the muzzle end of
the barrel is raised for closing the breech. By
the depression of the muzzle end of the bar- 55
rel and the advance motion of the sliding rod
the coiled spring described is compressed,
and on the raising of the muzzle end of the
barrel the compressed spring produces the re-
turn motion of the rod and assists the rising 60
motion of the barrel. By the action of the
mechanism described, the hammer is cocked
on the opening of the breech end of the bar-
rel, and the rod by which it was cocked with-
drawn by the shutting down of the breech 65
end of the barrel, so as to leave the hammer
free to fall. The mechanism described is ap-
plicable to single and double barrel guns.

We will now proceed to describe, with ref-
erence to the accompanying drawings, the 70
manner in which our invention is to be per-
formed.

Figures 1 and 2 represent in longitudinal sec-
tion, partly in elevation, the breech end of a
double-barrel dropdown gun containing cock- 75
ing mechanism constructed according to our
invention, the stock and other parts of the gun
being omitted. In Fig. 1 the barrels are rep-
resented shut down and the hammers dis-
charged, and in Fig. 2 the breech ends of the 80
barrels are represented lifted from the break-
off for opening the gun and the hammers
cocked. Fig. 3 represents in plan the fore-
end of the gun separately. Fig. 4 is a detail
view of the cocking-rod. Fig. 5 represents 85
one of the cranked levers carried by the fore-
end separately. Fig. 6 represents one of the
locks detached, with an addition, as hereinafter
explained; and Fig. 7 represents a part of
the same. 90

The same letters indicate the same parts in
the several figures of the drawings.

As the cocking parts at each side of the
double gun are alike in construction and ac-
tion, we will, for convenience of description, 95
describe the cocking parts at one side only.

a is the barrel, turning on the axis *b*, and *c*
is the body of the gun. *d d'* is the fore-end,

fixed to and moving with the barrel *a*, as usual. Sliding in the oblique opening *e* in the body *c* of the gun is a rod, *f*, by the motion of which, effected as hereinafter explained, the hammer 5 *g* is cocked. The said sliding cocking-rod *f* passes from below the axis *b* to the rear end of the body *c*, and terminates opposite the breast of the hammer *g*. The motion of the cocking-rod *f* is limited by a stop-pin, *h*, working in a cut-away part in the side of the rod, and the said rod is urged toward the muzzle end of the barrel by the coiled spring *i*. This spring takes a bearing at one end against a shoulder on the rod *f*, and at the other end against a shoulder made in the body *c*, as represented.

In the joint part *d*² of the fore-end *d* is a cranked lever, *k* *k*², turning on the pin or center *l*. The short upper arm, *k*, of this lever is 20 nearly horizontal and the long arm *k*² is nearly vertical when the parts of the gun are in their normal positions, Fig. 1. The said cranked lever *k* *k*² is so arranged with respect to the sliding cocking-rod *f* that its long arm *k*² bears against the lower end of the said rod, while the short upper arm, *k*, of the cranked lever bears upon a shoulder, *m*, made at the 25 front end of the body *c*.

On depressing the muzzle end of the barrel 30 *a*, for raising the breech end for charging the gun, the center *l*, on which the cranked lever *k* *k*² turns, being carried by the fore-end, is depressed with the said barrel. The cranked lever *k* *k*² is thereby made to turn upon its 35 center *l*, the short arm *k* being prevented from descending by the shoulder *m*, on which it bears. The result of this arrangement is that as the muzzle end of the barrel descends the long arm *k*² of the cranked lever is made to 40 move toward the break-off, pushing forward the sliding rod *f*, the upper end of which, bearing against the breast of the hammer *g*, cocks the said hammer, as illustrated in Fig. 2, which hammer is retained in its cocked position by

the sear *n* engaging with the bent in the said 45 hammer. By the depression of the muzzle end of the barrel *a* and the advance motion of the sliding rod *f* the coiled spring *i* is compressed, and on the raising of the muzzle end of the barrel for closing the breech end the 50 said compressed spring produces the return motion of the rod *f* and assists in the rising motion of the barrel *a*. By the withdrawal of the rod *f* on closing the breech the cocked hammer is free to fall for discharging the gun. 55 Thus the gun is cocked on opening the breech end of the barrel and the cocked hammer left free for discharge on the closing of the breech end.

Instead of causing the cocking-rod *f* to act 60 directly on the breast of the hammer *g*, it may act upon a small arm hung in front of the said breast, as illustrated in the lock shown in Fig. 6 and separately in Fig. 7, where *p* is the arm upon which the cocking-rod acts, the said arm 65 being jointed to the lock-plate at *p*². The lower free end of the arm *p* carries an anti-friction roller, *q*, which bears against the breast of the hammer.

Having now described the nature of our invention and the manner in which the same is to be performed, we wish it to be understood that we claim as our invention—

The combination, with the hammer of a dropdown gun, of the oblique cocking-rod *f*, 75 working in the body, the bearing-shoulder *m* on the said body, and the cranked lever *k* *k*², carried by the joint part *d*² of the fore-end *d*, the said cranked lever being arranged in the fore-end and with respect to the cocking-rod 80 and bearing-shoulder, and operating substantially as hereinbefore described, and illustrated in the accompanying drawings.
